UNITED STATES PATENT OFFICE.

HENRI BARON, OF MONTREAL, QUEBEC, CANADA.

DESIGN FOR A LADY'S BAG.

Application filed September 15, 1923. Serial No. 7,214. Term of patent 3½ years.

To all whom it may concern:

Be it known that I, HENRI BARON, a citizen of the United States of America, and a resident of Montreal, in the Province of Quebec, Dominion of Canada, have invented a new, original, and ornamental Design for a Lady's Bag, of which the following is a specification, reference being had to the accompanying drawing, forming part thereof.

I claim:

The ornamental design for a lady's bag, as shown.

HENRI BARON.

Witnesses:

B. ROLNI,
HECTOR HASPECK.
